UNITED STATES PATENT OFFICE.

BENJAMIN F. JACKSON, OF VERSAILLES, INDIANA.

WAVE-GRAVITY PUMP.

1,250,315.

Specification of Letters Patent. Patented Dec. 18, 1917.

Application filed April 27, 1917. Serial No. 164,900.

To all whom it may concern:

Be it known that I, BENJAMIN F. JACKSON, a citizen of the United States, residing at Versailles, in the county of Ripley and State of Indiana, have invented a new and useful Wave-Gravity Pump, of which the following is a specification.

The object of my invention is to provide a novel pump operated by the waves, having a novel float shaped to meet as nearly as practicable the perpendicular force of the waves. It is further my object to provide a mechanism adapted for the employment of either one or a series of pumps; and to provide novel lift and gravity pumps adapted to be operated by the single float which I have devised. It is also my object to provide a series of either lift or force pumps or to provide pumps of each of these types. It is further my object to provide novel means for adjusting the position of the pumps to give greater flexibility to the apparatus.

I attain these and other objects of my invention by the mechanism illustrated in the accompanying drawings, in which—

Figure 1 is a top plan of the float and the connecting frame; Fig. 2 is a side elevation of the invention illustrating its use in connection with a lift pump; Fig. 3 is a detail edge view of the adjustable pump rod; Fig. 4 is a side view of adjustable pump rod; Fig. 5 is a detail vertical section of my lift pump; Fig. 6 is a section on line 6—6 of Fig. 3; Fig. 7 is a vertical section of my force pump; and Fig. 8 is a horizontal section on line 8—8 of Fig. 7. Similar numerals refer to similar parts throughout the several views.

Referring to the accompanying drawings, I provide a novel float or buoy 1 mounted on the outer end of a suitable frame 2 which is pivotally mounted at 3 to a stationary frame or anchor posts 4 which are substantially anchored. The frame 2 is reinforced by the lateral braces 5 to secure the maximum of resistance to the lateral force of the waves. The parallel side members 6 of frame 2 are aligned with the anchor posts, as illustrated. To a beam 7 positioned adjacent the float 1 are attached the shafts 8 of suitable pumps. The buoy or float 1 is elongated, being considerably longer than wide with the center of the surface of the float raised and sloping slightly toward the edges. By providing a float much longer than wide the maximum of wave and gravity force may be utilized. I prefer to provide a

float three or four times as long as wide and set parallel with the wave, so that the whole under surface is subject to the buoyancy of the wave force, and on settling the force of gravitation can be almost all utilized as the float being narrow will reach the maximum depth in the trough of the waves. In its operation on the force pump this is the result required. A suitable banister rail 9 encircles the deck of the float. The bottom of the float has a long sloping curve from the front for a distance of approximately two thirds the width before the lowest point is reached from which point the bottom of the float is slightly concave. This shape of surface is arranged in order to accommodate the float to the perpendicular force of the waves in order that the maximum of wave force may be caught and utilized. The float is provided with a suitable man-hole cover 10 to permit of ready access to the interior in the event that repairs are needed. Attached to the pump shafts I provide novel mechanism for adjusting their length to high and low tide conditions. This adjustability is effected by means of a hollow shaft 11 suitably attached to beam 7 and having a second section 12 working therein. The sectional shaft 12 is provided with suitable cogs 13. Shaft 11 is provided with a slotted portion 14, to permit of the operation of the locking mechanism. Suitable cranks 15 are mounted in shaft 11 as shown in Fig. 4. They are provided with lugs 16 arranged to engage cogs 13 of shaft 12, as illustrated in Fig. 6. Cranks 15 are held in locked position normally by springs 17, illustrated in Fig. 4. The cogs 13 extend almost the entire length of shaft 12 and permit of a considerable extension or contraction of the pump shaft to suit varying tide conditions. The lug on the upper crank locks the inner shaft 12 from rising and the lug on the lower locks it from falling through the outer shaft 11; the arrangement of the lug may, however, be reversed, as in Fig. 6, without departing from the principle of my invention.

I may provide either a single pump or a series of either lift or force pumps, or preferably a combination of lift and force pumps. In my preferred arrangement lift pumps are provided at extreme distances from the power center and force pumps equi-distant from, though nearer the power center than the lift pumps, or vice versa, so as to secure better equilibrium. The lift pumps are operated

2 by the buoyant wave force and the force pumps by the weight of the mechanism. The pump cylinders are of a size proportionate to the weight and displacement of the buoy 5 or float and are connected by suitable pipe lines to a suitable reservoir or tank at any practicable distance or height desired.

Referring to Fig. 5 of the accompanying drawings a lift pump is shown having a casing 18 having slots 19 in its lower portion said slotted portions forming legs secured to a concrete base at 20. Within the cylinder 18 is a pistonhead 21 to which are secured piston rods 22 which are bent as shown at 15 23 and extend upwardly outside the casing 18 for a suitable distance and then bent inwardly again as shown at 24 and connected to the shaft 8. The top of the casing 18 is provided with a valve 25 adapted to seat in 20 a valve seat 26. Said valve is limited in its downward movement by clips 27 as shown. Near the top of the cylinder casing 18 is connected a line pipe 28 which leads to the tank or reservoir on the shore.

25 With reference to Fig. 7 a force pump is shown in which a cylinder 29 is shown in which reciprocates a piston 30 said piston being connected to the rod 8 by means of legs 31. The piston 30 is provided with a valve 32 seating in a valve seat 33. The valve 32 is provided on its top with a spider 34 said spider having pronged ends 35 which loosely surround the legs 31 and act as a guiding means for the valve, as shown in Fig. 8.

35 Referring again to Figs. 3 and 4, to the lower end of shaft 12 is provided a casting 36 having an L-shape extension 37 at the bottom thereof, said L-shape extension being bifurcated, as shown in Fig. 4. The upper end 40 of the rod 8 is provided with two laterally extending loops or eyes 38 which are engaged over the bifurcated ends of the L-shape extension 37. Secured to the face of the casting 36 is an inverted T-shaped brace 39 45 which swings from its upper end 40, its lower end being engaged under the bifurcated extensions 37 thus bracing said bifurcated portions and securing the loops 38 thereon. The members 37 may be provided 50 with eyes to accommodate a locking pin 41 suspended from the casting 36 by means of a chain or the like 42.

Referring to Fig. 1 and Fig. 2, I provide suitable runways or alleys, 43 leading to all 55 parts of the framework where frequent visits may be required and also from the framework to the buoy or float 1. These alleys may be of any suitable width and are strongly banistered on each side.

60 I may provide suitable gages near the extreme pumps to show the increase or decrease of volume of water; and I may provide a corresponding gage on the solid section of the adjustable shaft to indicate the necessity 65 of shortening or lengthening the shaft with

the changes of tide. The gage indicates units of length above the center point of the basic piston stroke. The pump cylinders are placed as near the buoy or float as conditions will warrant. In case the waves are regularly of great height the pumps may be placed much nearer the line of anchor posts and correspondingly farther from the buoy or float. The tops of cylinders preferably are inclined from the perpendicular. The 70 pump cylinders are of a size proportionate to the weight and displacement of the float, and are connected by pipe lines 28 to a suitable reservoir or tank at any practical distance or height desired. The operation of 75 the invention as disclosed in the foregoing description of its construction consists of the reciprocation of the pumps operated from the pivotally mounted frame 2 by means of the rise and fall of the float in consequence 80 of the action of the waves. The peculiar form of the bottom portion of the float makes it possible to utilize the greatest amount of power from the waves. The pump-shafts may be adjusted by the operation of cranks 85 90 95 100 105 110 115 120 125 130 controlling the sectional shaft 12 so as to lengthen or shorten the pump shafts to suit varying tide conditions. As the tide rises it is necessary that the shaft be increased in length; and the reverse occurs when the tide falls. To lengthen the pump shaft the lower lug crank is operated and as the float rises the inner shaft section is allowed to drop one or two cogs, as may be required, when the crank is allowed to return to locked position. As the tide falls the shortening of the shaft is accomplished by drawing the upper lug from its locked position by the operation of the upper crank 15 as the float is rising, and the inner shaft is allowed to rise the required distance in the outer section as the float falls. The crank is then allowed to return to locked position. The lift pumps are operated by the upward movement of the float with an incoming wave. The force pumps are operated by the weight of the frame 2 and float 1 and the attached mechanism as the float descends on a receding wave by gravity. The movement of the valves in the pumps is limited by the means illustrated in Figs. 5 and 7 of the accompanying drawings.

What I claim is:

1. In a device of the class described, a float having a far greater width than length and having a convex forward portion and a gently concaved bottom portion to utilize the maximum perpendicular force of the waves, in combination with a plurality of pumps operatively connected with the single float described.

2. In a device of the class described, a single elongated float, convex in its forward portion and concave on its bottom portion, anchor means, a frame to the outer end of

- which the float is mounted the frame being pivotally secured to the anchor means, lift pumps adjustably connected to the frame and operated by its upward movement, and force pumps adjustably connected to the frame and operated by the weight of the frame and the float when a wave recedes, a plurality of pumps being operated by the single float.
3. In a device of the class described, the elongated arcuate float shown, a pivotally mounted frame to which the float is secured, anchor means to which the frame is mounted, the float having a manhole cover in its upper portion, means for affording access to said cover to permit a workman to enter the float, lift pumps attached to the frame and operated by the buoyant wave force, force pumps spaced apart from the lift pumps and attached to the frame to be operated by the force of gravity as a wave recedes and lowers the float, the plurality of pumps being operated by a single float, and pipes leading from the respective pumps to the shore, substantially as set forth.
4. In combination with an elongated float having a concave bottom portion and a convex front portion, a connecting frame, anchor means to which the frame is pivotally mounted, a plurality of pumps operated by the single float, and sectional shafts adjustably connecting the pumps and the frame to permit adjustment to varying tide conditions.
5. In combination with an elongated float having a concave bottom portion, a frame to the outer end of which the float is se-
- cured: anchor means to which the frame is pivoted; and sectional shafts connecting the pump and the frame, said shafts comprising an outer shaft member and an inner shaft member, the inner shaft member having cogs, and the outer shaft member having a slotted portion, the said shafts also having resiliently controlled cranks carrying lugs arranged to engage the aforesaid cogs to lock the inner shaft at any desired position and permitting adjustment to varying tide conditions, and a plurality of pumps operatively connected to the aforesaid shafts, all of the pumps being actuated by the above described elongated float.
6. A wave gravity pump comprising anchor means, an elongated float convex in front and concave beneath to afford maximum utilization of wave force, means pivotally supporting the float, adjustable sectional shafts operatively connected with said float and actuated by the movement of the float, one or more lift pumps and one or more force pumps, each of said pumps being operatively connected with an adjustable sectional shaft to permit adjustment to varying tide conditions, and adjustable locking members for regulating the adjustment of the aforesaid pump shafts and adapted to lock them in any desired adjusted position as required by tide and wave conditions, all of the aforesaid pumps being operatively connected by the aforesaid elements with the aforesaid elongated float, whereby a plurality of pumps are operated by a single float.

BENJAMIN F. JACKSON.
